(57)

CLAIM

The ornamental design for inflatable blower, substantially as shown and described.

DESCRIPTION

FIG. 1 is a perspective view of its front, right and top surfaces;

FIG. 2 is a perspective view of its back and left;

FIG. 3 is a perspective view of its back, right and bottom;

FIG. 4 is a plan view of its front;

FIG. 5 is a plan view of its back;

FIG. 6 is the plan view on the left;

FIG. 7 is the plan view on the right;

FIG. 8 is a plan view of its top surface; and,

FIG. 9 is a plan view of its bottom surface.

1 Claim, 9 Drawing Sheets
